UNITED STATES PATENT OFFICE.

WILLIAM HUMBOLDT CLANDENING, OF CARMAN, MANITOBA, CANADA.

AUTOMATIC VENTILATOR-CONTROLLER.

1,093,314.

Specification of Letters Patent. Patented Apr. 14, 1914.

Application filed August 29, 1912. Serial No. 717,751.

To all whom it may concern:

Be it known that I, WILLIAM H. CLANDENING, a subject of the King of Great Britain, residing at Carman, Manitoba, 5 Canada, have invented certain new and useful Improvements in Automatic Ventilator-Controllers; and I do hereby declare that the following is a full, clear, and exact description of the invention, such as will enable others skilled in the art to which it 10 pertains to make and use the same.

The invention to be hereinafter described relates to automatic ventilator operating mechanisms.

15 In order to more clearly disclose the construction, operation, and use of the invention, reference should be had to the accompanying drawings forming part of the present application.

20 Throughout the several figures of the drawings like reference characters designate the same parts.

In the drawings: Figure 1 is an enlarged 25 sectional view of the actuating mechanism; Fig. 2 is a cross section on line 2—2 of Fig. 1; Fig. 3 is a side elevation of the invention, applied; Fig. 4 is a lateral cross section through one of the windows, showing the connections; and Fig. 5 is an enlarged 30 sectional view showing the means for returning the window to closed position.

The main objects of the invention are to provide a simple, efficient, durable, economical, and compact means for automatically 35 controlling the operating mechanism of car windows and ventilators, in accordance with and in proportion to the variations of temperature.

40 Referring to the drawings in detail, 1 indicates a sliding rod provided with suitable connections leading to the various windows or ventilators to be operated. One end of this rod is yieldingly connected to the lower end of a slotted bell crank lever 2, the opposite end of the lever being slidably connected to a piston rod 3 which has a free traveling movement in an upright cylinder 4. The lower end of this piston rod is provided with a piston head 5 which rests upon and is 45 actuated by a column of oil or other fluid sensitive to variations in temperature. This fluid is contained in a pipe or tube which extends for a considerable length within the car, building, or other construction in which 50 the device is to be used. It is connected to the cylinder 4 by an elbow 7 or the like.

The amount of expansion, and the consequent movement of the piston head 5, depends upon the length of the column of fluid and this, in turn, depends upon the length of 60 pipe 6. Therefore, in order to make the device highly sensitive, it is only necessary to have the pipe 6 of considerable length.

The invention may be used either with a fixed pivot or with a movable pivot for 65 the lever 2. For summer weather, the season when the greatest and most complete ventilation is needed, the movable pivot is used. This movable pivot comprises a spool or roller 8 playing freely in the elongated 70 slot 9 of the lever 2. The roller 8 is carried by the end of an arm projecting from a piston rod 10 slidably mounted in a cylinder 11 and provided with a piston head 12 adapted to be actuated by a column of fluid 75 in a tube, well, or pipe 13 connected to the bottom of the cylinder 11. The parts 10, 11, 12, and 13 are all substantially the same as the parts 3, 4, 5, and 6 and are operated in the same manner. But, they are arranged 80 on the outside of the wall and exposed to atmospheric temperatures. Thus, during very hot summer weather, the pivotal point 8 will be caused to approach the upper end of the slot 9, thereby lengthening that arm 85 1. This, in turn, increases the length of stroke of the rod 1, thereby swinging the windows to a more widely open position. However, this does not in any way alter or change the 90 degree of temperature at which the lever 2 will be actuated, as will be obvious. Lowering of the pivotal point 8 by drop in atmospheric temperature will have the reverse effect. Springs 14, or any other suitable device may be used for returning the window to normally closed position. In the drawings springs, only, have been shown.

The operation is as follows: The fluid contained by pipe 6 will expand as the temperature in the car rises. As the fluid expands it will act on piston 5 to raise rod 3. As rod 3 is raised it will lift the outer end of the bell crank lever 2 and revolve the lever on its pivotal point 8. This will draw the 100 rod 1 forward and open the windows against the action of the springs 14. As previously described, the pivotal point 8 of the bell crank lever is raised or lowered according to the temperature of the outside air. By 105 this means, the extent to which the windows are opened will be automatically regulated.

so that in cold weather they will be opened but a slight distance while in hot weather they will be opened to their full extent.

It is thought that the operation and use 5 of the invention will be clear from the preceding detailed description.

Changes may be made in the construction, arrangement, and disposition of the several parts of the invention without in any way 10 departing from the field and scope of the same, and it is meant to include all such within this application wherein only a preferred form has been disclosed.

Having thus fully described my invention, 15 what I claim as new and desire to secure by Letters Patent is:

1. In combination, a movable rod, a window, connections between said rod and window, a bell crank lever connected to said 20 rod, a piston, means for operating said piston by expansion, a rod carried by said piston, connections between said rod and the aforesaid movable rod, a second piston, means for operating the same by expansion, 25 a movable pivot for the bell crank lever carried by said piston, and sliding connections between said pivot and the lever.

2. In combination, a centrally slotted bell crank lever, a movable pivot therefor slidably operative in the slot, a movable rod carrying said pivot, a pivot head secured to the lower end thereof, a casing containing said head and exposed to the atmosphere, expansion and contraction means for raising and lowering the head according to thermo-atmospheric variations, said means being contained by the casing, a second movable rod connected to one arm of the bell crank, a piston head connected to the lower end thereof, a casing containing the piston head, 35 a second casing connected therewith and at right angles thereto and containing an element susceptible to thermal variations, a slidably mounted rod connected to the other arm of the bell crank lever, a window, connections between the rod and the window, and means for keeping the window normally closed.

In witness whereof I have hereunto set 40 by hand in the presence of two witnesses.

WILLIAM HUMBOLDT CLANDENING.
